CONCRETE FLOOR AND CEILING
CONSTRUCTIONClement Everett Burbank and Burritt A.
Cushman, Bedford Hills, N. Y.

Application February 10, 1934, Serial No. 710,712

10 Claims. (Cl. 72—66)

This invention relates to a concrete floor and ceiling construction. More particularly it relates to a concrete floor and ceiling construction which is fabricated from previously formed blocks and joists.

It is an object of this invention to provide a fabricated concrete floor construction which will give a beamed ceiling effect in the room below.

Another object is to provide an improved floor construction employing concrete blocks and joists which may be manufactured away from the location of the building.

Another object is to provide a concrete floor construction which can be quickly assembled from its previously manufactured component parts.

Another object is to provide a concrete floor construction which does not require the use of forms or molds during its assembly.

Another object is to provide a concrete floor construction which can be more quickly and less expensively constructed than prior floors of like nature and which is light and strong.

Other objects and advantages will become apparent as the invention is described in connection with the accompanying drawing:

In the drawing:—

Figure 1 is a perspective view of a partly constructed floor embodying the principles of our invention.

Figure 2 is a perspective view of a block used in constructing the floor.

Figure 3 is a detail cross section view through a portion of the floor around a joist.

Referring to the drawing, a beam or wall 10 supports spaced joists 12a, b, c and d, the spacing of the joists depending upon the dimensions of blocks 13a and 14a, b, c, and d, which are placed between the joists. When the blocks are in place the grout 16 is poured in over them and unites or bonds with them and with the joists to form a floor and ceiling of monolithic nature.

The beam or wall 10 may be considered as a primary supporting means and the horizontal parallel joists 12a to 12d may be considered as secondary supporting members for the blocks 13 and 14 and the grout 16. There will be a plurality of joists between the vertical supports or columns (not shown) and a plurality of rows of blocks, each row being between a pair of joists. In referring to blocks we do not include slabs which extend from one column or vertical support to another, and which cannot be manually positioned by one or two men on the job, or which require the use of forms in assembling them in their final position.

Referring more particularly to the individual components of the floor, the joists 12a, b, c, and d, are precast and formed of concrete preferably according to the method described in our copending application, Serial No. 710,711 filed concurrently herewith. This may be done at the building site or at a remote point from which the joists can be transported to the desired location. The joists are of inverted T-shape in cross section. The lower or tension part 12—1 is of greater width than the upper or compression part 12—2 but the height of the compression portion is usually greater than the tension portion. Obviously, however, the dimensions may be varied to suit the requirements of particular usage. Steel rods 15 12—4 and 12—5 are embedded in the tension and compression portions and extend lengthwise of the beam for reenforcement. Conventional shear reinforcements are also provided.

By reason of the lesser width of the compression part 12—2 shoulders 12—6 are formed between it and the tension part. These shoulders form rests for the blocks 14a, b, c, and d, which preferably are made of cement and a lightweight aggregate. The joists are spaced just far enough apart so that only the edges of the blocks rest on the shoulders 12—6. In order to insure the spacing of the sides of the blocks from the faces of the joists, fillets 12—7 are formed on the joists at the junction of the compression and tension parts. 20 These fillets prevent the edges of the blocks from coming in contact with the side faces of the joists. However, other means may be provided to prevent the side faces of the joists and blocks from coming into contact. Thus, the grout 16 which is poured over the blocks can fill in between the faces of the joists and blocks and bond with them. 25

As a further means to provide spacing between the joist and block faces, the side faces of the blocks are inclined so that the blocks have the 30 form of rectangular truncated pyramids. This inclination of the side faces of the blocks also provides a space between the side faces of adjacent blocks such as 14a, b, c and d, so that the grout can fill in between them and bond with them to 35 form a floor of monolithic nature.

The blocks 14a, etc., are preferably made of greater length than width so that the joist spacing may be varied by laying the blocks with either their long edges adjacent or their short edges adjacent.

The height of the blocks will preferably, though not necessarily, be less than the height of the compression portion 12—2 so that the blocks will be completely covered over by the 55

grout which may extend up to the top surface of the joists.

It will be observed that if the blocks are placed on the shoulders with their adjacent edges touching that no form will be required to hold the grout but only a barrier or baffle at the ends of the joists, for which an ordinary board will suffice. The bottoms of the blocks will thus be the ceiling of the room below our improved floor construction, and the tension parts of the joists will give the appearance of beams. Thus our invention provides not only a strong, light, easily constructed floor but also gives a beamed ceiling effect.

Another advantage of our construction is that the joists and blocks employed in making it are light and easily handled by one or two workmen.

Many modifications within the scope of our invention will occur to those skilled in the art, therefore we do not limit ourselves to the specific embodiments shown.

We claim:—

1. A concrete floor or ceiling construction comprising precast joists of inverted T-shape providing longitudinally extending shoulders on the side faces of the joists, precast blocks having their bottom faces resting upon said shoulders in abutment with each other, the side and end faces of said blocks being upwardly inclined providing recesses for the accommodation of grout between adjacent blocks and between the joists and the blocks, and grout bonding said joists and blocks.

2. A concrete floor or ceiling construction comprising precast joists of inverted T-shape providing longitudinally extending shoulders on the side faces of the joists, precast blocks having their bottom faces resting upon said shoulders in abutment with each other, and means on said joists preventing the side faces of said blocks and joists from touching.

3. A concrete floor or ceiling construction comprising precast joists each having a tension part and a compression part, the tension part being wider than the compression part to form a shoulder, precast blocks having their bottom faces resting on said shoulders, and means located at the junction of said compression and tension parts to hold the side faces of said blocks from the side faces of the joists, and grout bonding said blocks and joists together.

4. A concrete floor or ceiling construction comprising precast joists of inverted T-shape providing longitudinally extending shoulders on the side faces of the joists, precast blocks having their bottom faces resting upon said shoulders in abutment with each other, the side and end faces of said blocks being upwardly inclined providing recesses for the accommodation of grout between adjacent blocks and between the joists and the blocks, and grout bonding the adjacent faces of said blocks to each other and said joists and blocks being of greater width than length whereby the spacing of the joists may be varied accordingly as the blocks are laid with their long or their short edges adjacent to one another.

5. In a concrete floor or ceiling construction having a plurality of parallel horizontal secondary supporting members supported adjacent their ends upon primary supporting means, and extending between said primary supporting means, said secondary supporting members comprising precast joists of concrete with means on the sides thereof for supporting blocks, in combination

with a plurality of precast concrete blocks of any desired aggregate supported on said means on the sides of the joists, said blocks being placed in abutment with one another, and grout bonding the adjacent faces of said blocks to each other and also bonding said joists and blocks together.

6. In a concrete floor or ceiling construction having a plurality of parallel horizontal secondary supporting members supported adjacent their ends upon primary supporting means and extending between said primary supporting means, said secondary supporting members comprising precast joists of concrete with longitudinally extending laterally projecting means thereon for supporting blocks, in combination with a plurality of precast concrete blocks of any desired aggregate having all of its faces imperforate and supported on said longitudinally extending means, in abutment with one another, and grout bonding the adjacent faces of said block to each other and also bonding said joists and blocks together.

7. In a concrete floor or ceiling construction having a plurality of parallel horizontal secondary supporting members supported adjacent their ends upon primary supporting means and extending between said primary supporting means, said secondary supporting members comprising precast joists of concrete with means on the sides thereof for supporting blocks, in combination with a plurality of precast solid concrete blocks of any desired aggregate, said blocks being supported in abutment with one another on said supporting means on the sides of said joists and having upwardly inclined side and end faces providing recesses for grout, and grout bonding the adjacent faces of said block to each other and also bonding said joists and blocks together.

8. In a concrete floor or ceiling construction having a plurality of parallel horizontal secondary supporting members supported adjacent their ends upon primary supporting means and extending between said primary supporting means, said secondary supporting members comprising precast joists of concrete with longitudinally extending laterally projecting means thereon for supporting blocks, in combination with a plurality of precast solid concrete blocks of any desired aggregate supported on said longitudinally extending means, in abutment with one another, the bottom surfaces of said blocks being in a plane above the bottom surfaces of said joists, whereby a beamed ceiling effect is produced, and grout bonding the adjacent faces of said blocks to each other and said joists and blocks together.

9. A concrete floor or ceiling construction comprising precast joists having longitudinally extending laterally projecting means providing shoulders on the side faces thereof, precast blocks having their bottom faces resting upon said shoulders in abutment with each other and above the bottom faces of said joists whereby a beam ceiling effect is produced, the side and end faces of said blocks being upwardly inclined providing recesses for the accommodation of grout between adjacent blocks and between the joists and the blocks, and grout bonding said joists and blocks.

10. In a concrete floor or ceiling construction having a plurality of parallel horizontal secondary supporting members supported adjacent their ends upon primary supporting means and

extending between said primary supporting means, said secondary supporting members comprising precast joists of concrete with means on the sides thereof for supporting blocks, in combination with a plurality of precast solid rectangular concrete blocks of any desired aggregate, said blocks being supported in abutment with one another on said supporting means on the sides of said joists and having upwardly in-

clined side and end faces providing recesses for grout, said blocks being placeable on said supporting means with their side faces adjacent or with their end faces adjacent, and grout holding the adjacent faces of said blocks to each other and also bonding said joists and blocks together.
